UNITED STATES PATENT OFFICE.

GEORGE HERBERT FEICK, OF BALTIMORE, MARYLAND.

INCANDESCENT-LAMP SOCKET.

1,210,290.

Specification of Letters Patent. Patented Dec. 26, 1916.

Application filed November 29, 1915. Serial No. 64,196.

To all whom it may concern:

Be it known that I, GEORGE H. FEICK, a citizen of the United States, residing in the city of Baltimore and State of Maryland, have invented new and useful Improvements 5 in Incandescent-Lamp Sockets, of which the following is a specification.

This invention relates to electric cord protectors and more specifically to devices of 10 this character for protecting an electric cord at its juncture with a fixture.

This invention has for its primary object 15 to provide a device of this character slid-able on the cord and provided with means for locking it upon the cord at the point sub-ject to the deteriorating action.

My invention also includes resilient means 20 for allowing the proper amount of flexibility between the cord and the protector.

Although in my drawings I have shown 25 my protector coöperating with a lamp socket, it is to be understood that the same can be used independently of any particular fixture.

Referring to the drawings:—Figure 1 is 30 a side elevation of the lamp socket showing my invention applied thereto. Fig. 2 is a longitudinal section through the protector showing a portion of the socket also in sec-tion. Figs. 3 and 4 are cross sectional views.

Referring to the drawings, the numeral 1 35 designates a casing slidably on a sleeve 2 of tapering outline. Held in close contact with the smaller end of the sleeve 2 by means of the inturned end 3 of the casing is one end convolution of a coil spring 4 shown en-circling the cord 5 at its juncture with the sleeve 2. The purpose of this spring 4 is to 40 give the proper amount of flexibility to the cord, and at the same time preventing acute angles being formed in the conductor cord, which would tend to break the insulating material forming one element of the cord. 45 This spring 4 has its remaining end convolution completely inclosed by an insulating bushing 6, that in turn encircles the cord. The sleeve 2 is provided with a slot 7 one wall 8 of which is arranged at an incline, 50 and to engage an inclined end wall 9 of a locking key 10, the latter being of a size to snugly fit the slot. This locking key 10 is provided with a bulged portion 11, disposed opposite an arcuate shaped depression 12 55 formed in the bore 13 of the sleeve that receives the cord 5.

From this arrangement it will be seen that when the key 10 is forced home by means of the sliding casing 1 the bulged portion 11 will force the portion of the cord into the de-pression 12 with the result that the protector as a whole is held against movement upon the cord and thus insuring the protector being held upon the cord at the point of wear. As stated before the protector is 60 shown associate with a lamp socket, but the same can be readily used independent of any fixture due to the fact of the gripping action between the cord and the sleeve which prevents relative movement of the protector 65 and the cord. For attaching the sleeve to the lamp socket I provide the former with a threaded shank 14 engaging the usual threaded extension 15 in one end of the lamp socket. Coöperating with the shank is the 70 set screw 16 passing through the tubular ex-tension 14 of the lamp socket 18 and shown binding against the threads of the shank. At this point attention is called to the fact that the bushing 6, spring 4 and casing 1 75 can be slid lengthwise of the cord inde-pendent of the sleeve so that the key 10 may be readily removed to allow the sleeve to be unscrewed from the lamp socket.

Obviously various changes could be made 80 in certain parts of the device by one skilled in the art without departing from the scope and spirit of the invention.

What I claim as new is:—

1. The combination with an electric cord, 90 of a protector therefor including a semi-conical sleeve having a longitudinal arcuate depression substantially centrally therein and extending lengthwise thereof, circular collars formed at each end in one piece with 95 said sleeve and encircling the electric cord, a locking key complementary to said sleeve and completing the conical contour there-with, said sleeve having its ends abutting against said collars, a bulged portion on said key disposed opposite the depression in said sleeve, a casing snugly fitting over said sleeve and key and binding the same closely together with the bulge portion forcing the electric cord into said arcuate depression, 100 and means for holding said casing in place about said sleeve and key.

2. The combination with an electric cord, 110 of a protector therefor including, a sleeve having a depression therein and a cut-away portion opposite said depression, integral collars at the ends of said sleeve encircling

the electric cord, one of said collars being beveled, a locking key fitted in the cut-away portion of said sleeve and engaging against the inner ends of said collars, one end wall 5 of said key being beveled to conform to the beveled wall of said collar, a bulged portion on said key disposed opposite said depression, and a casing snugly fitted over said sleeve and key and binding the same closely

together with the bulged portion pressing 10 the electric cord into said depression.

In testimony whereof I affix my signature in presence of two witnesses.

GEORGE HERBERT FEICK.
